UNITED STATES PATENT OFFICE.

NELS T. NELSON, OF ATTLEBORO, MASSACHUSETTS, ASSIGNOR TO J. F. STURDY'S SONS CO., OF ATTLEBORO FALLS, MASSACHUSETTS, A CORPORATION OF MASSACHUSETTS.

BRACELET.

Application filed January 29, 1924. Serial No. 689,231.

To all whom it may concern:

Be it known that I, NELS T. NELSON, a citizen of the United States, residing at Attleboro, in the county of Bristol and 5 State of Massachusetts, have invented certain new and useful Improvements in Bracelets, of which the following is a specification.

This invention relates to bracelets or 10 chains of the extensible type: and has for its object to provide a bracelet of this character comprising a plurality of box-shaped links which are elastically connected by links having springs acting upon them to 15 normally yieldably hold the box-links in abutted position.

A further object of the invention is to so construct the links of the chain that they may be manually manipulated to be readily 20 separated whereby one or more of the links may be removed or fresh ones inserted to regulate the operating length of the chain.

A further object of this invention is to construct the box-links of a single piece of 25 metal folded into shape and secured by rolling the edges together.

A still further object of the invention is to form the box-connecting links in U-shape, 30 the ends of these links being compressible or adapted to be sprung toward each other and are provided with means at their ends by which they may be detachably connected to the ends of the next adjacent box-link when in extended position.

A still further object of the invention is to so construct the members of the chain that when contracted to its normal position the parts are locked against separation.

With these and other objects in view, the 40 invention consists of certain novel features of construction, as will be more fully described, and particularly pointed out in the appended claims.

In the accompanying drawings:

45 Figure 1 is a side elevation showing my improved chain formed as a bracelet and connected to opposite sides of a watch.

Figure 2 shows the shape of a blank as 50 cut from sheet stock from which one of the box-shaped links of the bracelet is constructed.

Figure 3 is a perspective view of one of the box-shaped links showing one end thereof as provided with an end wall having side 55 slots through which the ends of the U-

shaped link extend to be connected to the next box.

Figure 4 is a perspective view of the box-link showing the opposite end thereof as provided with T-shaped slots for the reception of correspondingly-shaped heads on the ends of the U-shaped link. 60

Figure 5 is a perspective view of the U-shaped link showing its T-shaped engaging ends. 65

Figure 6 is a plan view partly in section showing a plurality of the box-links as separated and the U-shaped links as connecting the box-links, one of the arms of one of these links being compressed towards 70 the other to enter one of the T-slots and engage the end of the next adjacent box-link. 75

Figure 7 is a top view partly in section showing the pair of middle box-links in a bracelet having their abutting ends permanently connected together and said boxes having U-shaped links extending outwardly from their opposite ends. 80

It is found in the practical construction of extensible bracelets of this character, of advantage to be able to disconnect one link from the other so that if one is broken it may be readily detached from the chain and a fresh one inserted. Then again, it is often found necessary to extend the length of the chain which may be readily accomplished by simply disconnecting the link and inserting an extra one and the chain may be shortened by simply removing one of the links and connecting the remaining links together. It is also found of advantage in bracelets of this character to elastically connect the box-links together and to so construct the different connecting links that when the chain is contracted and the links are in their normal position that the parts are locked against being disconnected one from the other; and the following is a detailed description of one means by which these advantageous results may be accomplished. 95

With reference to the drawings, 10 designates the box-links which are preferably constructed from one piece of metal by being blanked out of sheet stock into the form illustrated in Figure 2, and then bent into the form illustrated in Figures 3 and 4 forming a top wall 11, a bottom wall 12, side walls 13, and one end wall 14 having slots 105 110

or spaces 15 on the sides thereof and an opposite end wall 16 having T-shaped slots 17 formed therein, the whole being locked together without the use of solder by rolling 5 the edges 18 of the side walls over those of the top wall.

These box-links are arranged to be releasably or detachably connected together by means of a U-shaped link 19 whose arms 10 or walls 20 are somewhat yieldable or resilient laterally and are formed at their ends with T-shaped heads 21 and the box links and U-shaped links are each elastically or extendably connected together by a spring 15 22 acting between them. A box link as set forth is such link in a chain that forms an inclosure having top, bottom, side and end walls and the connecting members between the links pass through openings in the adjacent end walls of the box links and are 20 practically inclosed therein when in normal position.

In assembling these parts the U-shaped link is inserted into one of the box-links, 25 the spring 22 preferably of the coil or helical type is also inserted into the box, one end resting against the bridge portion 23 of the U-shaped link while its opposite end engages the end wall 14 of the box-link, and 30 the arms of this link are preferably of a length to normally extend a short distance out through the slots 15 in its box which assembly is completed before the edges 18 of the side walls 13 of the box are rolled over 35 the top plate 11 thereof.

After these combined links have been thus assembled, it is only necessary in order to connect the different box links, to draw outwardly the arms 20 of the U-shaped link 40 from its box link and then first pass the T-shaped end 21 of one of the arms through the corresponding opening 17 in the end wall of the next adjacent box, and then compress or bend inwardly the other arm of 45 this U-link, as illustrated in Figure 6, and pass this end into engagement with the other T-shaped openings in this box link and when released the natural resiliency of the stock of the U-link will cause these arms to spread 50 automatically and enter the narrow portion of the T in the box link where they are retained by the inherent spring of the stock and when released the spring coil 22 serves to draw the adjacent ends of the boxes together 55 completely housing the U-shaped links and forming a continuous chain of boxes which are elastically connected and may be yieldably extended as desired by the application of an endways tension on the 60 chain.

When the spring 22 acts upon the U-shaped link to house it in its normal position in its box, it will be seen that the edges of the wall 14 serve to prevent the lateral 65 compression of the arms 20 and therefore,

positively prevent this U-shaped link from becoming disengaged from its box-link in which its ends are secured while the U-shaped link is in its normal position, it being only necessary to extend this link and bend its ends inwardly toward each other to have its arms become disengaged from the walls of this adjacent link by manual manipulation.

In some instances, particularly where the 75 chain is used as a bracelet having attaching members such as hooks 24 at its ends to be attached to a watch 25, it is found of advantage to provide a double link in the middle of this bracelet constructed after the 80 manner illustrated in Figure 7, in which these links 26 are permanently connected end to end as at 27 and each is provided at its outer ends with U-shaped links 19, the 85 ends of which are detachably connected in the manner above described to the T-shaped ends of the next adjacent box-link.

My improved construction of chain or bracelet is very practical to manufacture, is 90 handsome and attractive in appearance when finished, the links may be readily connected and disconnected from each other by manual manipulation when fully extended and are permanently locked against such disconnection when in their normal or contracted position.

The foregoing description is directed solely towards the construction illustrated, but I desire it to be understood that I reserve 100 the privilege of resorting to all the mechanical changes to which the device is susceptible, the invention being defined and limited only by the terms of the appended claims.

I claim:

1. A bracelet structure comprising a series of box links, means for elastically connecting said links including a resilient connector member slidably housed in the box link and responsive to manual manipulation to detachably connect said links whereby links may be inserted or removed at will to change the effective length of said bracelet.

2. A bracelet structure comprising a series of box links, a member normally housed by and slidably in one box link and being detachably connected to the next adjacent box link by manual manipulation, and a spring acting through said member to draw said box links together.

3. A bracelet structure comprising a series of box links, a connector member slideable in said links and having resilient arms to be snapped into engagement with the next adjacent link, a spring for normally holding said connector housed, and permitting it to be exposed for attaching and detaching manipulation by hand.

4. A bracelet structure comprising a series of box links, a connector member in each of said box links and having resilient arms

- adapted to be pressed inwardly to permit disengagement of the next adjacent box link when said member is extended from its box link. 45
5. A bracelet structure comprising a series of box links, a connector member in each of said box links and having resilient arms adapted to be pressed inwardly to permit disengagement of the next adjacent 50
- 10 box link when said member is extended from its box link, and means being provided for preventing detachment of said connector member when said links are in normal position. 55
- 15 6. A chain structure comprising a series of box links connected by U-shaped links having resilient portions and normally housed in said box links, said resilient portions being yieldable to be detachably connected to the next adjacent box when extended, each box being provided with an abutment, and a spring acting between said abutment and a portion of the U-link to 60 yieldably cause the boxes to abut. 65
- 20 7. An extendible chain structure comprising a series of boxes, a U-shaped link slidably housed in each box, the arms of each link being yieldable and so detachably connected to the adjacent box when in extended 70
- 25 position, and means being provided for locking the link against being detached when in normal position. 75
8. A chain structure comprising a series of boxes, a U-shaped link normally housed in one box and having its ends connected to an adjacent box, the ends of said link being detachable from their engaged box by moving said ends toward each other. 80
- 30 9. An extendible chain structure comprising a series of boxes, a U-shaped link normally housed in each box and having resilient arms adapted at their ends to be compressed toward each other to be releasably connected to the next adjacent box when 85
- said link is extended from its housing box, and a spring acting on said link to normally and yieldably hold the boxes in abutting relation. 45
10. An extendible chain structure comprising a series of boxes, a U-shaped link normally housed in each box and having resilient arms adapted at their ends to be manually compressed toward each other when in extended position to be releasably connected to the next adjacent box, a spring in each box acting to yieldably hold its link in housed position and the boxes in abutting relation and means being provided in each of said boxes for preventing a detaching movement of its link arms when in normally housed position. 60
11. A bracelet construction comprising a series of boxes each formed of a single piece of sheet metal having T-shaped openings in one of its end walls, a U-shaped link 65 slidable in each of said boxes having T-shaped ends engaging the correspondingly-shaped opening in the next adjacent box, and yieldable means acting between each box and its contained link for holding said boxes in contact and permitting said construction to be extended. 70
12. A bracelet construction comprising a series of boxes, each comprised of front and back plates supported and held in spaced relation by end and side walls, a U-shaped link in each box between said plates having its end projecting through one of said end walls, means cooperating between the end wall of the next adjacent box and said projecting ends for attaching each link to its adjacent box, and spring means acting between an end wall of the box and its link for normally holding the adjacent boxes in contact. 85

In testimony whereof I affix my signature.

NELS T. NELSON.
